CLAIM

The ornamental design for a display screen portion with icon as shown and described.

DESCRIPTION

The FIGURE is a front view of a display screen portion with icon shown on a monitor according to the claimed design. The dash-dot broken lines in the drawings define the bounds of the claimed design and form no part thereof.

The dash-dot-dot broken lines in the drawings showing the monitor illustrate environmental subject matter that forms no part of the claimed design. The relative positioning of the display screen portion and icon on the monitor forms no part of the claimed design.
